(57) **CLAIM**

The ornamental design for a frame profile, as shown and described.

DESCRIPTION

FIG. 1 is a front elevational view of a frame profile; FIG. 2 is a fragmented right side view of the frame profile of FIG. 1;

FIG. 3 is a fragmented left side view of the frame profile of FIG. 1; and,

FIG. 4 is a fragmented top plan view of the frame profile of FIG. 1.

The frame profile has been broken on one end to disclose indefinite length.
